CARRIAGE-FEED MECHANISM FOR TYPE-WRITING MACHINES.

997,137.

Specification of Letters Patent.

Patented July 4, 1911.

Application filed June 7, 1906. Serial No. 320,541.

To all whom it may concern:

Be it known that I, OSCAR C. KAVLE, a citizen of the United States, residing at Syracuse, in the county of Onondaga and State of New York, have invented a new and useful Improvement in Carriage-Feed Mechanisms for Type-Writing Machines, of which the following is a specification.

This invention relates to carriage feed mechanisms for typewriting machines, that is to the feed or escapement mechanism employed for producing the step-by-step or letter space movements of the carriage.

The invention is especially applicable to front-strike typewriting machines in which the type-bars are pivoted on a segment below the platen to strike the front side of the platen, but all of the features of the invention are not, however, restricted to such type of machine.

The primary objects of the invention are to produce a carriage feed mechanism which will cause the carriage to feed full letter spaces immediately after and only after the impact of the type-bars with the platen, and which will enable the machine to be operated with great speed; and to so construct and arrange the feed mechanism that no perceptible power from the key levers is required for its operation, and so that the carriage can be set back for a new line, or a portion thereof, without the employment of the usual ratchet device with its consequent noise and annoyance.

Other objects of the invention are to provide a series of small, light actuators for the carriage escapement, each of which is moved independently of the others by impact from one or more type-bars, whereby the parts requiring movement to operate the carriage escapement are lighter and can be operated more rapidly than where a single device is employed for all of the type-bars; to arrange the actuators intermediate of the type-bars and the escapement and provide them with retracting springs in such manner that they return to initial position independently of the part which they actuate, whereby they assist in moving the type-bars immediately out of contact with the platen before the carriage is set in motion by the escapement; to arrange the actuators in such manner that they serve as dust guards for the type-bar bearings; to mount the actuators, their springs and the universal bar

or part actuated by the actuators, on a single bracket whereby they can be assembled and adjusted on the bracket before the latter is secured in the machine and can be more readily mounted in and removed from the machine; and to improve the carriage feed mechanisms of typewriting machines in the respects hereinafter described and set forth in the claims.

In the accompanying drawings, consisting of three sheets: Figure 1 is a longitudinal sectional elevation of portions of a typewriting machine provided with a carriage feed mechanism embodying the invention. Fig. 2 is a fragmentary rear elevation thereof, partly in section in line 2-2, Fig. 1, showing the normal holding position of the carriage escapement. Fig. 3 is a perspective view, partially broken away, of the supporting bracket for the universal bar actuators, a portion of the actuators being mounted on the bracket. Fig. 4 is a perspective view of the universal bar detached. Fig. 5 is a fragmentary sectional elevation of the supporting bracket for the universal bar actuators and the parts mounted thereon, in line 5-5, Fig. 2. Fig. 6 is a sectional elevation of the carriage escapement, showing the parts in a different position from that shown in Fig. 2. Fig. 7 is a rear elevation of the type-bar segment, a portion of the type-bar hangers and one type-bar, showing the universal bar actuators in section. Fig. 8 is an enlarged sectional elevation of the escapement, showing another position of the parts. Fig. 9 is an elevation of a modified construction of the carriage escapement. Fig. 10 is a sectional elevation of one of the universal bar actuators.

Briefly stated, the carriage feed mechanism hereinafter described in detail is organized and operates as follows:

The type-bars are pivoted below the platen to swing upwardly and rearwardly to strike the same, an oscillating universal bar is arranged in rear of the type-bars and is connected to the carriage escapement which is arranged adjacent to the carriage, as usual, and produces a letter space movement of the carriage each time the universal bar is actuated. Between the type-bars and the universal bar is arranged a series of independent or separately movable actuators, one of which is adapted to be struck and moved rearwardly by each type-bar and

when so moved oscillates the universal bar. The several actuators move the one universal bar, but each actuator is arranged in the path of and adapted to be actuated by only a portion of the type-bars. Only one actuator is operated at a time, and the universal bar is short and light so that the parts moved in operating the escapement are lighter and capable of greater speed than a single actuator large enough for all of the type-bars to strike would be. The actuators are not attached to either the type-bars or the universal bar but are struck by the type-bars and by their movement oscillate the universal bar. The operative movement of the actuators is opposed by springs which return the actuators to their initial position independently of the universal bar and assist in moving the type-bars out of contact with the platen immediately after the impact without waiting for the return of the universal bar or the carriage escapement to which it is connected. The escapement mechanism is of novel construction which will be described.

Like letters of reference refer to like parts in the several figures.

A represents the frame of the machine, B the platen, C the carriage on which the platen is rotatably mounted and which, as usual, is moved transversely of the machine by any suitable power-driven means (not shown), D one of the type-bars, which are pivoted in an arc below the platen, and E the key levers for operating the type-bars. These parts may be of any usual or preferred construction and arrangement. In the machine illustrated, which is of the front-strike type, the carriage travels transversely of the machine on a suitable track *f* on a shift frame *F* which is pivoted at its ends to the main frame at *f'*, in any suitable manner, in rear of the platen, whereby the carriage can be shifted vertically for the purpose of printing different case characters, it being understood that type-bars are provided with a plurality of sets of type. The type-bars are pivoted between forwardly projecting side plates or portions of hangers *g* separately secured on the segment, see Figs. 1 and 7. The side plates of the hangers have upwardly and rearwardly curved front ends *g'* which serve as guides for the type-bars in approaching the printing point and also as stops for the universal bar actuators, as will be described, and the key levers are connected to the type-bars by auxiliary levers *h*, one of which is shown in Fig. 1, which are pivoted at their lower ends, are connected at their upper ends to the type-bars and have sliding connections between their ends with the key levers. Owing to the cam shape of the slots *h'* of these connections the type-bars are caused to approach the platen with an

accelerating motion, as fully explained in Letters Patent No. 819,365, granted to H. A. Moyer and E. G. Latta on May 1, 1906. The shape of the slots *h'* is ordinarily such that the key levers exert little or no pressure on the type-bars when the latter reach the platen, and the slots can be, and sometimes are, shaped so that the type-bars are carried through the last portion of their travel wholly by their momentum, in which case the type-bars are free to rebound for a short distance from the platen even if the key levers are held down.

The carriage feed mechanism to be described operates most satisfactorily in connection with type-bars having an accelerating motion, but any means for producing such accelerating motion of the type-bars could be employed.

I represents the actuators or parts for transmitting movement from the type-bars to the universal bar. They are arranged in the arc of a circle concentric with the arc of the type-bar pivots with their front ends located in rear of and adapted to be struck by the type-bars just as the latter strike the platen, and they are mounted in any suitable manner to reciprocate forwardly and rearwardly independently of each other. Each actuator preferably consists of a straight wire or stem having a front end or head *i* which is wide enough to be struck by several of the type-bars. In the construction shown, each head is wide enough to be struck by seven of the type-bars, and as there are forty-two type-bars employed in the machine illustrated six actuators are used, and as the type-bars are spaced farther apart near the ends of the segment than at the center thereof, the actuator heads are made of different widths as required. Such arrangement, however, is not necessary. A separate actuator could be employed for each type-bar, or one for each of several groups of type-bars of any desired number, and if it is desired to have all of the heads of the actuators of the same width this can be effected by arranging the actuators toward the ends of the segment to be engaged by a less number of type-bars than those at the center of the segment. The heads shown consist of curved pieces of sheet metal and are secured to the stems by inserting the latter between oppositely bent bridge pieces *i'* on the heads, to which the stems are soldered, see Fig. 10. The heads could, however, be secured to or formed on the stems in any other suitable manner. The heads of the actuators are curved concentrically with the arc of the type-bar pivots, so as to engage the type-bars at equal distances from the pivots, and are located just above the portions of the hangers to which the type-bars are pivoted in rear of the curved ends *g'* of the hangers which form stops to limit

the forward movement of the actuators. The hangers thus prevent the actuators from oscillating, and the actuator heads from dust shields for the type-bar bearings. 5 The heads have upturned front flanges i^2 for the type-bars to strike and these flanges also act to throw any dust or dirt accumulating on the heads rearwardly over the type-bar bearings when the actuators are 10 operated by the type-bars.

The actuators are all preferably mounted to slide forwardly and rearwardly on a bracket K, see Figs. 1 and 3. This bracket is made from a single piece of sheet metal 15 and has a horizontal top portion k' which is secured by screws, or otherwise, to the top plate of the machine frame, and depending front and rear plates k^2 k^3 having holes k^4 through which the actuator stems pass 20 and in which they bear. The actuators are normally held forward in the position shown in Fig. 1 and are returned to such position after actuation by suitable springs L, which preferably consist of strips of spring metal 25 each having one end bent forwardly and screwed or otherwise secured to a forwardly bent lug or portion l of the back plate of the bracket. The free end of each spring L is opposite to and bears against the rear end 30 of one of the actuator stems. As the actuator stems are, as above stated, arranged in an arc, the lugs for the two center springs are located at the upper portion of the rear plate of the bracket and the springs extend 35 downwardly therefrom, while the lugs for the other springs are located at the lower portion of the back plate and the springs extend upwardly at an inclination therefrom in opposite directions on opposite sides 40 of the center of the plate. Springs of the same length can thus be employed on a smaller bracket. By bending the lugs and springs, as shown, displacement of the springs is prevented. The tension of the 45 springs can be regulated as required, by bending the securing lugs therefor upwardly or downwardly.

M represents the universal bar which is 50 arranged horizontally in rear of the supporting bracket K for the actuators, is journaled to oscillate, and is provided with projecting arms m , each of which has a forwardly bent end opposite to and bearing against one of the springs L for the actuators between the ends thereof. The universal bar also has a rearwardly extending 55 central arm m' which is connected to the carriage escapement. As the universal bar is arranged horizontally, while the actuators are arranged in an arc, and it is desirable 60 to produce equal movements of the bar by the several actuators, the arms m of the universal bar are made of different lengths and bear upon the springs at the points necessary to secure this result, see Figs. 2 and

4. The universal bar preferably consists of a shaft journaled at its ends in rearwardly bent bearing lugs or portions m^2 of the rear plate of the bracket K, and the arms m and m' are formed from a single piece of sheet metal plate which is soldered in a longitudinal groove in the shaft or is otherwise secured thereto. The arms of the universal bar are preferably formed with ribs or flanges to give them the requisite rigidity. 75 The central arm m' is preferably connected by a spring m^3 to a rearwardly bent arm or portion m^4 of the back plate of the bracket K, whereby the universal bar is normally held in and is returned after actuation to 80 the normal position shown in Fig. 1. All of the actuators I and their returning springs L, and also the universal bar with its retracting spring, are mounted on the single bracket K so that these parts can be assembled and properly adjusted before the bracket is secured in the machine, and they can all be removed as a unit at any time, by detaching the bracket K from the top plate of the machine. When a type-bar is 85 actuated it will strike the actuator in rear thereof a quick sharp blow and will, by its momentum, drive the actuator rearwardly and through the spring L bearing against said actuator and the corresponding arm of 90 the universal bar, rock said universal bar and operate the escapement. The actuators and springs form operative connections between the type-bars and the universal bar, but they are not attached to either of said 95 parts and the springs are free to return the actuators to the normal position without waiting for the return of the universal bar and parts of the escapement connected thereto. The actuators are also exceedingly 100 light and therefore can be started back quicker than the heavier universal bar, thus enabling the actuators to react instantly on the type-bars and throw them out of contact with the platen before the latter can be 105 moved and thereby preventing the blurring of the impressions. The springs L also form elastic cushions between the actuators and the universal bar and, therefore, greatly reduce the noise. Another advantage of this 110 construction is that lighter springs than usual can be used for returning the key levers, and the touch is made correspondingly easier. The type-bars are returned so quickly as to avoid possibility of collision 115 even when the machine is used by the most rapid operators and thus avoid one of the objections to the front-strike machine in which the type-bars all approach the platen from the same side. The type-bars return 120 to their normal position with greater speed than is possible in a machine in which the universal bar is long enough for engagement by all of the key levers, or even long enough 125 for direct engagement by all of the type- 130

bars. These results are due to the comparatively short light universal bar, and separate light actuators therefor which are not attached to the bar and are free to return 5 in advance of the return movement of the universal bar.

The actuators and universal bar above described can be employed in connection with any suitable carriage escapement for producing 10 the letter space movements of the carriage, but the novel escapement herein-after described is preferably employed. The separate independently movable actuators could also be employed to actuate a 15 different sort of a universal bar or common device connected to the carriage escapement.

The carriage is connected to and moved to the left by any usual or suitable power-driven means, and the step-by-step or letter 20 space movements thereof are caused by an escapement mechanism in the usual manner, the escapement mechanism, however, being preferably constructed as follows, see Figs. 2, 6 and 8: O represents the escapement 25 wheel which is secured to the rear end of a shaft p journaled in a bearing p' on the shift frame and provided, as usual, with a gear pinion p^2 meshing with a toothed rack p^3 on the carriage. The escapement wheel 30 has radial teeth, the opposite sides of which have the same angularity or inclination with reference to the radial center lines of the teeth. Q is an escapement lever which is arranged parallel with the escapement 35 wheel, or in the plane thereof, and is pivoted in any suitable manner between its ends, on a part q of the shift frame. One end of the lever is adjustably connected to the rearwardly projecting arm m' of the universal 40 bar, for instance, by a rod q' consisting of sections joined by a turn-buckle, and the other end q^2 of the lever is adapted to engage between the teeth of the escapement wheel and has opposite faces q^3 q^4 adapted 45 by reason of their angularity to bear flat against the opposing faces of two adjacent teeth of the escapement wheel. This end of the lever has, between the inclined faces, a face q^5 curved on an arc concentric with the 50 escapement wheel. The escapement wheel and lever are both carried by the shift frame and the pivotal connection between the lever and its operating rod q' is located nearly on the axial line about which the shift frame 55 swings, so that with a slight looseness in this connection the carriage can be shifted without movement of the escapement lever with the consequent friction and wear on the same and the escapement wheel. The 60 strain is very slight on the connection between the lever and rod q' and nothing at all when the carriage is being shifted. This arrangement is a decided improvement over the known ones in which the escapement 65 wheel is mounted on the shift frame and its

lever or holding dog on the main frame, so that the one must move laterally on the other in shifting the carriage, or in which the wheel and lever are both on the main frame and the rack bar must move laterally on its 70 controlling pinion.

R represents a dog which is pivoted to the escapement lever at the opposite side of the pivot thereof from the end q^2 of the lever, and is adapted to be held yieldingly in an 75 intermediate position, shown by full lines in Fig. 6, by a spring S which, in the construction shown in Figs. 2 and 6, is fixed at one end to the end q^2 of the lever and bears at its free end against the heel of the dog, 80 which is preferably flat. The dog can be deflected to opposite sides of this central position, as indicated in Fig. 2 and by broken lines in Fig. 6, and will be returned to the central position in either case by the spring 85 S. The heel of the dog extends farther from the dog pivot toward the attached end of the spring than in the opposite direction, with the result that less force is required to swing the dog rearwardly or to the dotted line 90 position shown in Fig. 6 than forwardly or to the position shown in Fig. 2. The purpose of this will appear from the description of the operation of the escapement. The forward movement of the dog toward 95 the pivot of the escapement lever is limited by a stop t of any suitable form on the escapement lever. In the construction shown in Figs. 2 and 6 the dog is pivoted in a slot 100 in the lever and the end of the slot forms the stop or shoulder t for the dog. In the modification shown in Fig. 9, the dog R' is slotted and pivoted on the lever Q' which passes through the slot and has side stop shoulders 105 t' for the dog. The spring for the dog can also be differently arranged, for instance, in the modification, Fig. 9, the spring S' is not secured to the escapement lever but to a fixed part s^2 of the shift frame. This spring 110 acts on the dog similarly to the other spring and also serves to press the lever toward the escapement wheel and therefore renders the returning spring m^3 for the universal bar unnecessary. This spring S' can be adjusted 115 as required, by first loosening its securing screw, and it is held, when adjusted, by tightening up the screw. In both constructions the pivots for both the escapement lever and the dog are preferably parallel with the axis of the escapement wheel, so that the lever and dog swing in the plane of the wheel, or in planes parallel therewith, instead of crosswise thereof.

The operation of the escapement is as follows: In Fig. 2 the dog R is in engagement with a tooth of the escapement wheel and is pressed by the wheel against the stop shoulder on the lever and holds the wheel against turning in the forward direction, indicated by the arrow, that is in the direc- 120 125 130

tion for feeding the carriage. Each time a type-bar is operated it will strike an actuator I which, through the connections described, will swing the escapement lever to the position shown in Fig. 8, thereby disengaging the dog from the tooth of the wheel and allowing it to be instantly swung by its spring to its intermediate position, shown in Fig. 8, ready to intercept the next tooth of the wheel when the lever returns to the initial position. The described movement of the lever throws its face q^3 against a tooth of the wheel and the lever will instantly rebound owing to the impact assisted by the spring m^3 , and place the dog in the path of said next tooth of the wheel, and this rebounding of the lever assisted by the spring m^3 will restore the escapement lever and dog and the universal bar to their normal positions before the carriage driving means can overcome the inertia of the carriage and feed the same and start the escapement wheel. Should the joints of the escapement become stiff so that the lever will not rebound as stated, the inclined face of the tooth of the wheel acting on the inclined face q^3 of the lever will force it back to the initial position. When the dog is engaged by said next tooth of the wheel, it will be swung on its pivot until it is arrested by engagement with the stop-shoulder on the lever and thereby stops the wheel. The dog has to deflect its spring in thus swinging on its pivot, as shown in Fig. 2, and the spring thus serves as a cushion to prevent jar in the stopping of the wheel. The quick rebounding action of the escapement lever is made possible in large measure by the employment of the described universal bar, which is very light and is moved by a quick sharp blow delivered by the type-bars which are driven with an accelerating motion and strike the universal bar actuators substantially at the instant the type-bars reach the platen, and of the universal bar actuators which are free to return to normal position or follow the type-bars as they rebound from the platen without waiting for the return of the universal bar. The universal bar and the connected escapement lever and holding dog are free to return to their normal positions, and do so return before the carriage driving spring has had time to overcome the inertia of the carriage and start the escapement wheel. During the forward movement of the wheel one of its teeth passes by the curved face q^6 of the lever and the lever, therefore, cannot be vibrated by the pressure of the wheel tooth on the dog and prevent the proper action of the dog in intercepting the next tooth of the wheel. The escapement will operate fairly well without the spring m^3 , but the spring is preferred. If the dog R were a rigid part of the escapement lever instead

of pivoted and spring-pressed, the escapement would work with a slowly moving universal bar, but if the lever is vibrated by a sudden impulse and rebounds from the wheel without waiting for the wheel to move, as above explained, a rigid dog will return into engagement with the tooth from which it was released by the movement of the lever before the carriage had time to move and thus prevent the escapement wheel from turning, unless an objectionably heavy driving spring for the carriage is used. With the pivoted dog and spring described it is impossible for the dog to return into engagement with the same tooth of the wheel.

The pivoted spring-pressed dog described, besides acting as a cushion for the carriage when it stops, also allows the escapement wheel to be turned backwardly, as indicated by the arrow in Fig. 6, to set the carriage back for a new line or portion thereof, and the usual ratchet and pawl are unnecessary. From Fig. 6 it will be seen that the dog can yield to permit such backward movement of the wheel, and as the dog can be moved backwardly with less strain on its spring than when moved forwardly, as explained, the action of the dog is practically noiseless. The leverage of the spring on the dog is such that the dog can swing backwardly without oscillating the lever on its pivot, but in case the dog should raise the lever, the movement thereof would be very slight as at such time one of the teeth of the wheel would be opposite to the curved face q^5 of the lever. If, from any cause, the end q^2 of the lever should swing between two teeth of the wheel, the action of the inclined face of the tooth on the inclined face q^4 of the lever would restore the lever to its normal position, and the only noise therefore made in the backward movement of the carriage would be that of the dog against its spring, which, as explained, is inconsiderable.

The relative arrangement of the dog and wheel is such that when the former is in holding position its face engages the face of the tooth on a line substantially at right angles to a line extending from the point of contact of the dog and tooth to the pivot of the escapement lever. There can, therefore, be but little wear on these faces and the escapement will operate for a long time without noticeable wear on these parts. The escapement has but one dog or part which in the normal operation of the escapement stops and holds the wheel and it therefore avoids the so-called "drop of the carriage" by permitting the carriage to feed one complete letter space the instant the dog is withdrawn from the wheel instead of the more common action of stopping the carriage twice for each letter-space. The escapement lever and the universal bar are posi-

130

tively connected and return to their normal positions, by the rebound of the escapement lever assisted by the spring m^3 connected to the universal bar, or by the action of the inclined teeth of the escapement wheel on the inclined face q^3 of the escapement lever.

On account of the described construction of the type-bar action, quick sharp blows on the key levers are required to make the impressions and release the escapement wheel, and the escapement will not operate with a blow that is not sufficient to produce an impression, so that the annoyance of having the carriage move when no impression is made is avoided. The escapement is preferably used with a type-bar action in which the type-bars have an accelerating motion, as described, but the escapement could be employed with other sorts of type-bar actions, whether actuated by the type-bars or other parts.

In the modified construction, shown in Fig. 9, the weight of the escapement is slightly reduced, and the spring m^3 for the universal bar is not required. The single spring S' serves to return the escapement lever to its normal position in addition to its functions of returning the dog to its normal intermediate position after deflection in either direction and cushioning the wheel as it comes to a stop.

I claim as my invention:

1. In a typewriting machine, the combination of a series of type-bars, independent actuators which are movable independently of the type-bars arranged to be operated by the type-bars as they approach the platen and to react on the type-bars to move them out of contact with the platen, a carriage escapement, and operative connections between the said actuators and said carriage escapement, substantially as set forth.

2. In a typewriting machine, the combination of a series of type-bars, independently movable actuators arranged in the paths of the type-bars to be struck by the type-bars and moved substantially simultaneously with the contact of the type-bars with the platen, means for yieldingly resisting the movement of actuators, a carriage escapement, and operative connections between said actuators and said carriage escapement, substantially as set forth.

3. In a typewriting machine, the combination of a series of pivoted type-bars, independently movable actuators each having a part adapted to be struck and moved by a plurality of the type-bars, a carriage escapement, and operative connections between said actuators and said carriage escapement, substantially as set forth.

4. In a typewriting machine, the combination of a series of pivoted type-bars, independently movable actuators which are detached from the type-bars, springs for

yieldingly holding said actuators in a position to be struck by the type-bars as they approach the platen, a carriage escapement, and operative connections between said actuators and said carriage escapement, substantially as set forth. 70

5. In a typewriting machine, the combination of a series of type-bars, independent endwise movable actuators arranged opposite to the type-bars, and each having a head adapted to be struck by a plurality of the type-bars, springs for holding said actuators in normal position, a carriage escapement, and operative connections between said actuators and said carriage escapement, 75 substantially as set forth. 80

6. In a typewriting machine, the combination of a type-bar action having a series of pivoted type-bars, a universal bar, independently movable actuators arranged to transmit movement from movable parts of the type-bar action to the universal bar, said actuators being detached from said universal bar, and a carriage escapement actuated by said universal bar, substantially as set forth. 90

7. In a typewriting machine, the combination of a pivoted type-bar, a universal bar, an actuator arranged between the type-bar and said universal bar to be moved by the movement of the type-bar and detached from said universal bar, and a carriage escapement actuated by said universal bar, substantially as set forth. 95

8. In a typewriting machine, the combination of a type-bar, a universal bar, an actuator arranged between said type-bar and said universal bar to be moved by the movement of the type-bar and detached from said type-bar and universal bar, a spring 100 for returning said actuator to normal position, and a carriage escapement actuated by said universal bar, substantially as set forth. 105

9. In a typewriting machine, the combination of a type-bar, a universal bar, an actuator arranged between said type-bar and said universal bar in the path of movement of the type-bar, a spring which is moved by said actuator and operates said universal bar, and a carriage escapement actuated by said universal bar, substantially as set forth. 110

10. In a typewriting machine, the combination of a series of type-bars, a universal bar, independently movable actuators for transmitting movement from the type-bars to said universal bar, a fixed stop for limiting the movement of the actuators in one direction, spring means for opposing the movement of the actuators in the opposite direction, and a carriage escapement actuated by said universal bar, substantially as set forth. 115 120

11. In a typewriting machine, the combination of a series of pivoted type-bars, a universal bar mounted to rock, independ- 125 130

- ently movable actuators operated by the type-bars in approaching the platen for rocking said universal bar, and a carriage escapement actuated by said universal bar, substantially as set forth.
12. In a typewriting machine, the combination of a series of type-bars pivoted in an arc, a universal bar which is arranged opposite to the type-bars and is shorter than the distance between the outermost bars of the series, independently movable actuators for transmitting motion from the type-bars to said universal bar, and an escapement actuated by said universal bar, substantially as set forth.
13. In a typewriting machine, the combination of a series of type-bars arranged in an arc, a universal bar arranged opposite to the type-bars, independently movable actuators arranged in an arc for transmitting motion from the type-bars to said universal bar, and means between said actuators and said universal bar for causing equal movements of said universal bar by all of said actuators, and an escapement actuated by said universal bar, substantially as set forth.
14. In a typewriting machine, the combination of a series of type-bars arranged in an arc, a universal bar arranged opposite to the type-bars, independently movable actuators arranged in an arc to transmit motion from the type-bars to said universal bar, and springs moved by said actuators and arranged to produce equal movements of said universal bar, and an escapement actuated by said universal bar, substantially as set forth.
15. In a typewriting machine, the combination of a series of pivoted type-bars arranged in an arc, a universal bar arranged opposite to said type-bars to rock and having projecting arms, independently movable actuators arranged opposite to the type-bars in an arc, springs which are moved by said actuators and bear against the arms of said universal bar to produce equal movements thereof, and an escapement actuated by said universal bar, substantially as set forth.
16. In a typewriting machine, the combination of a series of type-bars, a universal bar, and an escapement actuated thereby, independently movable actuators arranged to be moved by the type-bars, springs actuated to transmit movement from the actuators to said universal bar and to restore said actuators to the normal position independently of said universal bar, substantially as set forth.
17. In a typewriting machine, the combination of a series of type-bars, hangers to which said type-bars are pivoted, an escapement, and independently movable actuators for said escapement having heads arranged to be moved by said type-bars, said hangers having parts constituting guides and stops for said actuators, substantially as set forth.
18. In a typewriting machine, the combination of a series of type-bars, hangers to which said type-bars are pivoted, an escapement, and independently movable actuators for said escapement having heads arranged to be moved by the type-bars, said hangers having projecting side plates which guide said actuators and form lateral supports for the type-bars when in contact with said actuators, substantially as set forth.
19. In a typewriting machine, the combination of a series of type-bars, an escapement, and a movable actuator for said escapement having a head arranged over the type-bar pivots to form dust shields therefor and adapted to be moved by the type-bars, substantially as set forth.
20. In a typewriting machine, the combination of a series of pivoted type-bars, an escapement, a movable actuator for said escapement having a flanged head arranged over the type-bar pivots in the path of movement of the type-bars, substantially as set forth.
21. In a typewriting machine, the combination of a series of type-bars, a carriage escapement, a plurality of movable actuators for said escapement arranged to be moved by the type-bars, and a detachable bracket supporting all of said actuators, substantially as set forth.
22. In a typewriting machine, the combination of a series of type-bars, a universal bar and an escapement actuated thereby, a plurality of actuators for said universal bar arranged to be moved by said type-bars, a detachable bracket supporting said actuators and said universal bar, and an escapement actuated by said universal bar, substantially as set forth.
23. In a typewriting machine, the combination of a series of type-bars, a universal bar, and an escapement actuated thereby, a plurality of actuators for said universal bar arranged to be moved by the type-bars, retracting springs for said actuators, and a detachable bracket supporting said actuators and springs, substantially as set forth.
24. In a typewriting machine, the combination of a series of type-bars, a universal bar and an escapement actuated thereby, a plurality of actuators for said universal bar arranged to be moved by the type-bars, retracting springs for said actuators, and a detachable bracket supporting said actuators, retracting springs and universal bar, substantially as set forth.
25. In a typewriting machine, the combination of a series of type-bars, a carriage escapement, a plurality of actuators for said escapement arranged to be moved by the type-bars, and springs for communicating

movement from said actuators to said escapement and restoring the actuators to the initial position, substantially as set forth.

26. In a typewriting machine, the combination of a series of type-bars, a universal bar and an escapement actuated thereby, a plurality of actuators for said universal bar arranged to be moved by the type-bars, and springs arranged with their free ends in engagement with said actuators and their central portions in engagement with said universal bar, substantially as set forth.

27. In a typewriting machine, the combination of a series of type-bars arranged in an arc, a universal bar arranged horizontally to rock and having arms of unequal length, an escapement actuated by said universal bar, a plurality of actuators for said universal bar arranged in an arc to be moved by the type-bars, and springs for communicating movement from said actuators to said universal bar, a portion of said springs being arranged within the arc and a portion without the arc of said actuators, substantially as set forth.

28. In an escapement for typewriting machines, the combination of a driven toothed wheel, a pivoted lever having at one side of its pivot a face to contact with the teeth of said wheel, which face is inclined so that the lever does not hold the wheel, a holding dog for said wheel pivoted to said lever at the opposite side of the lever pivot and arranged to clear one tooth of said wheel substantially simultaneously with the contact of said inclined face with another tooth, and means for vibrating said lever to cause said inclined face to contact with the teeth of the wheel, said means normally permitting the rebound of the lever to its original position, substantially as set forth.

29. In an escapement for typewriting machines, the combination of a driven toothed wheel, a lever pivoted to swing in a plane substantially parallel with the plane of rotation of said wheel and having at one side of its pivot a part to contact with the teeth of the wheel, one of said contacting parts of the lever and wheel being shaped so that the lever does not hold the wheel, a holding dog for the wheel movably mounted on said lever at the opposite side of the lever pivot and arranged to clear one tooth of the wheel substantially simultaneously with the contact of said part of the lever with another tooth, and means for vibrating said lever to cause said part thereof to contact with the teeth of said wheel, said means normally permitting the rebound of the lever to its original position, substantially as set forth.

30. In an escapement for typewriting machines, the combination of a driven toothed wheel, a pivoted lever having a part to contact with the teeth of the wheel, one of said contacting parts of the lever and wheel be-

ing shaped so that the lever does not hold the wheel, a holding dog for the wheel pivoted to said lever and arranged to clear one tooth of the wheel substantially simultaneously with the contact of said part of the lever with another tooth of the wheel, means for vibrating said lever to cause said part thereof to contact with the teeth of said wheel, said means normally permitting the rebound of the lever to its original position, a spring for swinging said dog on its pivot when it clears the tooth of the wheel and yieldingly opposing the movement of the dog by the wheel, and a stop against which said dog strikes to stop the wheel, substantially as set forth.

31. In an escapement for typewriting machines, the combination of a driven toothed wheel, a centrally pivoted lever having a part to contact with the teeth of the wheel, one of said contacting parts of the lever and wheel being shaped so that the lever does not hold the wheel, a dog pivoted to said lever for holding the wheel against movement in one direction, said dog being capable of yielding to allow the movement of the wheel in the opposite direction, a spring for returning said dog to the initial position, means for vibrating said lever to cause said part thereof to contact with the teeth of said wheel, and means for returning said lever to normal position immediately after its contact with the teeth of the wheel, substantially as set forth.

32. In an escapement for typewriting machines, the combination of a driven toothed wheel, a pivoted lever having a part shaped to strike and rebound from the teeth of the wheel without holding the wheel, a dog pivoted to the lever for normally holding the wheel against movement in one direction and capable of swinging on said lever in opposite directions from an intermediate position, a spring for returning said dog to such intermediate position from either direction, and means for vibrating the lever, substantially as set forth.

33. In an escapement for typewriting machines, the combination of a driven toothed wheel, a pivoted lever having a part with two inclined faces for engagement with the teeth of the wheel, means for vibrating said lever, and a dog pivoted to said lever for holding said wheel against forward movement, said dog being capable of movement by said wheel in opposite directions, said inclined faces of the lever permitting the wheel to turn in either direction and restore said lever to its normal position in the event that said part of the lever is not retracted from the wheel by said vibrating means, substantially as set forth.

34. In an escapement for typewriting machines, the combination of a toothed wheel, a pivoted lever having opposite inclined

faces for engagement with the teeth of said wheel, and a face between said inclined faces which is curved substantially concentric with said wheel, a dog pivoted to said lever for holding said wheel and adapted to be swung in opposite directions from an intermediate position by said wheel, and means for vibrating said lever, substantially as set forth.

35. In an escapement for typewriting machines, the combination of a driven toothed wheel, a pivoted lever, a dog pivoted on said lever at one side of the fulcrum for the lever, and means for vibrating said lever, said lever having an inclined face at the 15 opposite side of its fulcrum arranged to engage a tooth of the wheel without stopping the wheel when the lever is vibrated to release said dog from the wheel, said wheel acting on said inclined face of the lever serving to positively restore said lever and place 20 said dog in holding position, substantially as set forth.

36. In an escapement for typewriting machines, the combination of a driven wheel 25 having teeth with opposite faces oppositely inclined with reference to the radial lines of the teeth, a pivoted lever having a part at one side of its pivot to contact with said inclined faces of said teeth, the inclination 30 of said faces of the teeth preventing said part of the lever from holding the wheel, a holding dog for the wheel pivoted to said lever and arranged to clear one tooth of the wheel substantially simultaneously with the 35 contact of said part of the lever with another tooth, and means for vibrating said lever to cause said part thereof to contact with the teeth of said wheel, said means normally permitting the rebound of the lever to its 40 original position, substantially as set forth.

37. In an escapement for typewriting machines, the combination of a driven toothed member, a lever pivoted to swing in a plane 45 substantially parallel with the plane of movement of said toothed member and having a part to contact with the teeth of said member, one of said contacting parts of the lever and member being shaped so that the 50 lever cannot hold said member, a dog which is movably mounted on said lever for engagement with said teeth successively to hold said member and is arranged to disengage a tooth substantially simultaneously 55 with the engagement of said part of the lever with another tooth, and means for vibrating said lever to cause said part thereof to strike a tooth and again clear the same without arresting the wheel and in advance 60 of the engagement of said holding dog with a successive tooth, substantially as set forth.

38. In an escapement for typewriting machines, the combination of a driven wheel 65 having teeth with inclined forward faces, a

pivoted lever having a part at one side of its pivot to contact with said forward faces of said teeth, the inclination of said forward faces of the teeth relative to the direction of movement of said part of the lever being 70 such that said part does not hold the wheel, a dog movably mounted on said lever at the opposite side of the lever pivot for engaging said forward faces of the teeth to hold said wheel from forward movement, and means 75 for vibrating said lever to cause said part thereof to contact with the teeth of said wheel, said means normally permitting the rebound of the lever to its original position, substantially as set forth. 80

39. In an escapement for typewriting machines, the combination of a driven toothed wheel, a pivoted lever having at one side of its pivot a part to contact with the teeth of the wheel, one of said contacting parts of the lever and wheel being shaped so that the lever does not hold the wheel, a holding dog for the wheel movably mounted on said lever at the opposite side of the lever pivot and arranged to clear one tooth of the wheel 90 substantially simultaneously with the contact of said part of the lever with another tooth, and means for vibrating said lever to cause said part thereof to contact with the teeth of said wheel, said means normally permitting the rebound of the lever to its original position, said lever having a face adjacent to said part thereof which is substantially concentric with said wheel for preventing recontact of said part with a tooth 95 until after a predetermined movement of said wheel, substantially as set forth.

40. In a typewriting machine, the combination of a main frame, a shift frame pivoted to the main frame, a carriage supported by said shift frame, a universal bar supported by the main frame, an escapement wheel, and a coöperating holding device therefor both supported by the shift frame, and connections between said universal bar and said holding device, substantially as set forth. 105

41. In a typewriting machine, the combination of a series of type-bars, means for imparting an accelerating motion to said bars, a universal bar actuated by the type-bars 110 substantially at the instant they complete their movements, a power-driven toothed wheel, a centrally pivoted lever operatively connected to the universal bar and having a part to contact with the teeth of said wheel, one of said contacting parts of the lever and wheel being shaped so that the lever does not hold the wheel, and a holding dog pivoted to said lever and arranged to clear one tooth of the wheel substantially simultaneously 115 with the contact of said part of the lever with another tooth, substantially as set forth.

42. In a typewriting machine, the combination of a series of type actions including

pivoted type-bars, a relatively small universal bar arranged substantially parallel with the plane in which the type-bars are pivoted, means operated thereby, and a plurality of universal bar actuators each acting to transmit motion from a plurality of the type actions for adjacent type-bars to said universal bar, substantially as set forth.

43. In a typewriting machine, the combination of a series of pivoted type-bars arranged with their pivots in an arc, a plurality of actuators arranged substantially

concentrically with said type-bars to be struck thereby, a carriage escapement, and means actuated by said actuators for operating the escapement, substantially as set forth.
